LAMP STOVE.

No. 406,991.

Patented July 16, 1889.

UNITED STATES PATENT OFFICE.

JOSEPH W. BROER, OF CHICAGO, ILLINOIS.

LAMP-STOVE.

SPECIFICATION forming part of Letters Patent No. 406,991, dated July 16, 1889.

Application filed April 27, 1888. Serial No. 272,008. (No model.)

To all whom it may concern.

Be it known that I, JOSEPH W. BROER, of Chicago, in the county of Cook and State of Illinois, have invented certain new and useful Improvements in Lamp-Stoves; and I do hereby declare that the following is a full, clear, and exact description thereof, reference being had to the accompanying drawings, and to the letters of reference marked thereon, 5 which form part of this specification, in which—

Figure 1 is a side elevation of my improved oil-stove, the heating-drum being partly broken away. Fig. 2 is a central vertical longitudinal section through the same with the drum removed. Fig. 3 is an end view, partly broken away. Fig. 4 is a top plan view of plate I. Fig. 5 is a detail view of plates E and C. Figs. 6 and 7 are detail views of the 15 burner-cones, and Fig. 8 is a view of the top plate of the drum.

This invention is an improved lamp-stove; and it consists in the novel construction and arrangement of parts hereinafter described 20 and claimed.

Referring by letters to the drawings, A represents the bottom frame of the stove, which is rectangular and provided with a cross-piece A' and with feet A''.

30 a are four upstanding lugs rising from the sides of frame A, and a' is a short stud rising from one end thereof.

a'' are perforated ears projecting laterally from the side rails of frame A.

35 B is the oil-tank, also rectangular, open at top and supported on frame A, being kept in position by lugs a and stud a'.

B' is a feed-pipe in the end of tank B.

40 b is an inclined division-plate secured transversely in tank B, at one end thereof, and having notches in its edges to permit the gradual flow of fluid from one compartment to the other, and it prevents undue splashing of the oil in the tank on the side below the 45 burner and overflowing of the joints when the stove is moved.

C is a dished metal plate supported on tank B, and C'' are perforated ears projecting laterally from the plate at points corresponding 50 to ears a'' of plate A.

c are bolts passed through the ears of plates A and C and binding them together, thereby securing tank B in place.

The depressed portion D of plate C forms the water-pan above the larger compartment of 55 tank B, in which it depends.

D' are wick-openings in pan D, and D'' are flanges surrounding said openings and rising above the surface of plate C, so that no water can enter tank B. At the other end of plate 60 C is formed a dish d, in which water may be placed or on which utensils can be laid.

E is a rectangular frame superimposed on plate C and provided with depending lugs E', the concaved ends of which rest upon the concaved ends of lugs a and support frame E thereon.

E'' are countersunk holes in the sides of frame E, and e e are bolts passed therethrough and engaging lugs a'' of frame A, 70 binding plate E in position.

e' are studs rising from the corners of frame E and concaved in their upper ends, as shown.

e'' are bifurcated lugs rising from the inner corners of frame E, and f'' is an upstanding 75 flange on the inner end of frame E between studs e'.

G is a plate having openings G', surrounded by depending flanges G''. This plate is set on flanges D'', its flanges G'' entering flanges 80 D''. Sheets of asbestos or non-heat-conducting packing are interposed between plate G and flanges D''. Plate G is beaded or flanged at its upper edges to shed fluids through openings G'.

g is a metal disk resting on frame E, its center being cut out to accommodate plate G and perforated for the passage of rods F which rise from plate E.

g' is an upstanding foraminous plate on 90 the periphery of disk g, having cuts at one side to accommodate the stems of the wick-ratchets.

The burner has a base-plate H', and in the present instance two wick-tubes H'' H'', 95 which project below base H' and are provided above said plate with ratchet-offsets h, in which work ratchets h', the stems of which project outside band g'. The ratchets h' are made wide, so that they will not cut the 100

wicks. The burner is placed over plate G and disk g, the depending portions of its wick-tubes entering the flanged openings of plate G. Base H' is perforated for the passage of rods F, upon which are nuts that hold the burner securely on plate E and bind plate G and disk g in position.

The heater-drum Z is constructed as follows:

10 I is a metal disk of proper diameter and provided with depending feet I', that rest upon studs e' of frame E, similarly to the mounting of frame E on frame A. From the sides of the inner feet I' of disk I project inclined studs i, from which in turn project lateral ears i', which engage the bifurcated lugs e'', and when drum Z is tilted back form hinge-joints therewith, so that drum Z is properly directed in its movements. When 20 thrown back the drum is partly supported by part d.

From the bottom of disk I depend two series of concentric flanges J, which are arranged to break joints, and are adapted to 25 evenly distribute the air to the burners.

J' J' are openings in disk I, through which the wick-tubes project. The openings are separated by a cross-bar J'', from which rises a screw-threaded rod j. Above openings J' are 30 secured the burner-cones K, a proper packing being interposed between the cones and disk. The cones are inclined both at sides and ends, as at k³ and k⁴, to insure equal air-drafts therethrough and prevent flickering of 35 the flame. The walls of the cones converge to a narrow wick-opening, and from the edges of this opening rise the slightly-diverging opposite flanges K', which concentrate the heat on the upper edge of the wick, causing 40 a more perfect combustion, and will keep the wick burned down to an even line should the wicks be raised too high. In practice it is found a thin wick will be burned off so that it will not smoke in about two minutes, 45 and a thick wick will be burned down in about five minutes, the greatest heat being at the junction of the flanges K' with the top edges of the cone.

k k are the chimneys placed over cones K, 50 formed with converging upper sides k', and are held in place by a double yoke K'', slipped on rod j and retained by a nut, as shown. When made of metal the chimneys are provided with mica sights. The lower edges of 55 the chimney may be flanged and engaged by angular dogs k⁸.

L is a sheet-metal cylinder surrounding the cones and chimneys and supported on disk I, being properly centered by a projection i', as shown, and having a proper sight opposite the chimneys.

M is a disk having a bead M' on its under surface, which engages the upper end of cylinder L and forms a tight joint therewith. 65 M'' are openings in this disk above chimneys k k, separated by a rib m', and m is a de-

pending angular flange on said disk, which serves to retain the heated air exterior to the chimneys in the drum and increase the heat radiated therefrom. Disk M is secured in 70 place by a nut on the rod j, which passes through an opening in rib m'. The rod j thus forms a bond to unite the several portions of the drum.

N is a serrated flange rising from the periphery of disk M, and n n are a series of studs rising therefrom and serving as supports for an oven or vessel which may be set thereon.

It will be seen that the entire stove can be 80 quickly taken apart for repairs or cleaning; also, that there is both an air-space and a water-space between the flame and oil, and that the packing is so disposed that it will materially assist in keeping the heat from 85 the oil.

The operation and other advantages of my invention, such as its peculiar joints, will be apparent from the foregoing.

Having thus described my invention, I 90 claim—

1. The herein-described oil-stove, comprising a base-frame having upstanding lugs a, the oil-tank supported thereon, the plate closing said tank and forming the water-pan 95 and having flanged wick-openings, substantially as described, and the burner and drum, and the plate supporting the burner and drum, having depending lugs E', that support the same on lugs a, all substantially as 100 specified.

2. The within-described oil-stove, consisting of the bottom frame A, having upstanding lugs a, the oil-tank supported thereon, the plate C, closing the open end of the tank 105 and bolted to frame A and formed with a water-pan D, and the plate E, having depending lugs E' resting on the lugs a of frame A and supported thereby above plate C, the drip-plate G, and the burner and drum supported 110 on plate E, all substantially as described.

3. The combination of the base-frame, and oil-tank, and burner-supporting plate E, having upstanding bifurcated lugs e'', with the disk I, having depending feet I' resting 115 on plate E, and inclined studs i, formed with laterally-projecting ears i', adapted to engage the lugs e'' and form hinge-joints therewith, all substantially as specified.

4. The oil-stove herein described, consisting of a base-frame, oil-tank, water-pan, and drip-plate, and the plate E, substantially as described, and the disk I, supported on plate E and carrying the heating-drum and burner-cones, and the burner having a base-plate supported on the frame E below disk I, all substantially as set forth.

5. The combination of the base-frame A, having upstanding lugs a, the oil-tank supported thereon, and the plate C, supported on 130 the oil-tank and bolted to frame A, with the plate E, having depending lugs E' resting on

lugs *a* of frame *A*, the burner carried on plate *E*, the disk *I*, having feet *I'* supported on plate *E*, the burner-cones and chimneys supported on the disk *I*, and the drum *Z*, supported on disk *I*, having a top disk *M*, formed with depending flanges *m m*, all substantially as and for the purpose specified.

In testimony that I claim the foregoing as my own I affix my signature in presence of two witnesses.

JOSEPH W. BROER.
